UNITED STATES PATENT OFFICE.

GEORGE KERR, OF DALLAS, OREGON.

LAMP-BURNER.

No. 821,171.

Specification of Letters Patent.

Patented May 22, 1906.

Application filed December 21, 1905. Serial No. 292,826.

To all whom it may concern:

Be it known that I, GEORGE KERR, residing at Dallas, in the county of Polk and State of Oregon, have invented certain new and useful Improvements in Lamp-Burners, of which the following is a specification.

This invention relates generally to improvements in the common type of slotted-dome oil-lamp burners, and more particularly seeks to provide an improved construction of burner of the type referred to, including in its make-up a valve or muffler device that becomes automatically operative to extinguish the flame whenever the lamp is tilted during a partial or total upsetting of the same, whereby to prevent the ignition of any of the oil that might flow from the bowl or reservoir.

My present invention in its more specific nature embodies an improved construction of the burner and extinguisher devices broadly disclosed in my copending application, Serial No. 281,488, filed October 8, 1905, and allowed November 27, 1905; and it seeks to provide a simplified arrangement of the extinguishing means, whereby the burner with the extinguishing devices can be the more economically manufactured and whereby the action of the muffler or extinguishing valves or plates will be rendered positive without the employment of special and delicately-mounted means on each plate for interlocking with the slot in the burner-dome when the plates automatically swing over the dome-slot during a tilting or dropping action of the lamp.

My present invention in its generic nature comprehends a burner of the type referred to, and means in the nature of a plate shaped to swing over the dome-slot, pivotally mounted on the said dome in such manner so it will frictionally engage with the dome after it is swung over the dome-slot, thereby automatically locking itself to its slot-closing position.

In its more complete nature my present invention comprehends in a burner of the type stated a pair of oppositely-disposed plates, each independently hinged on the outer side of the dome to automatically swing over the dome-slot when the lamp is tipped in either direction, the slotted dome being so shaped and the plates pivotally mounted on said dome in such manner that as either of said plates is swung over the slot in the dome it will become frictionally interlocked with

the dome member and remain to its slot-closing position.

In its details of construction my present invention embodies certain features, all of which will be hereinafter fully described, specifically pointed out in the claims, and illustrated in the accompanying drawings, in which—

Figure 1 is a side elevation of a portion of an oil-lamp with my improved construction of burner applied. Fig. 2 is a similar view showing the lamp in the act of tipping over and illustrating the manner in which my improved extinguishing devices act. Fig. 3 is a vertical section of the burner tipped in a direction opposite to that shown in Fig. 2. Fig. 4 is a detail perspective view of the slotted dome or crown portion of the burner with the extinguishing-plates at their open or normal position. Fig. 5 is a plan view of the same. Fig. 6 is a horizontal section thereof on the line 6 6 on Fig. 7. Fig. 7 is a longitudinal section of the same on the line 7 7 on Fig. 6. Fig. 8 is a diagrammatic transverse section of the slotted dome member and the pivoted plates, illustrating the correlative curvature and pivotal connection of the plates and the curvature of the dome member. Fig. 9 is a perspective view of one of the muffler or extinguisher plates.

In the drawings the lamp 1 may be of any of the ordinary types of oil-lamp, and the burner B in its general construction is also of the usual type, the only special or new feature of construction in my form of burner being that the slotted dome b has its upper or crown portion of substantially semicircular shape in transverse direction, the curvature in the form shown being on an arc having the point x as the center. The semicircular portion of the dome may extend the full width of the dome-body; but to effect the results desired it need extend only to the raised projections b' b' at opposite sides of the slot b², from which points the dome-body may have any desired ornamental shape.

In the present form of my invention I use two muffler-plates or valve members. In the present arrangement the plates 1^a 1^a have a special curvature with respect to the curvature of the dome. Each plate has pendent apertured ears 1^b 1^b for engaging the screw studs or pintles 2 2^a, that project from the dome member b in the longitudinal plane of the dome-slot and which are arranged eccentrically with respect to the curvature of the

slotted crown portion of the dome, the pintle for one plate being disposed at one side of the center point x of the circle of the slotted dome and the pintles of the other plate on the 5 other side of said point x , the reason for which will presently appear. Each plate 1^a 1^a is curved on the arc of a circle, and the curvature is such that in swinging back or away from the slot b² to the normal position 10 said plates will swing freely and out of contact with the crown portion of the dome and with a space between the plates and the dome greater than the thickness of the plates 1^a 1^a. The plates are held to their normal or 15 dropped position (away from the slot b²) by reason of their lower edges resting on the projections b' b', and by reason of the shape of the plates and the manner in which the plates are pivotally connected to the dome member 20 b they automatically retain their normal or open position under the ordinary handling of the lamp.

So far as described it will be readily apparent that the plates 1^a and 1^a by their own 25 weight are maintained at their open or normal position. By pivotally connecting the plates as stated and curving them in transverse direction on an arc to provide for space between the plates and the slotted crown also 30 allows for either of the plates swinging over the slot when the lamp is tipped in either direction, it being understood that when the plate at one side drops over the slot it has free movement under the other plate by reason of 35 the space between the other plate and the slotted dome. Furthermore, by reason of the curve of the plates being on an arc curvature with the curve of the crown portion of the dome when either of said plates is swung 40 over the slot the front and rear edges of the plate will snugly engage the dome-top, and thereby effect a positive closure of the dome-slot at both edges thereof.

Having thus described my invention, what 45 I claim, and desire to secure by Letters Patent, is—

1. A lamp-burner having an extinguisher which comprises a plate shaped to swing over the flame-slot, said plate being pivotally 50 mounted on the burner, whereby to frictionally engage the burner-body when swung over the slot therein, for the purposes described.

2. In a lamp-burner of the character described, the combination with the slotted dome; of a pair of oppositely-disposed plates, each independently hinged on the outside of the dome whereby either of said plates is adapted to automatically swing over the 55 dome-slot when the lamp is tipped in either direction, each plate being shaped to frictionally engage the dome when swung over the slot therein.

3. In a lamp-burner of the character described, a pair of oppositely-disposed plates 65 pivotally mounted on the slotted dome portion, either of said plates being adapted to close over the dome-slot when the lamp is tipped in either direction and shaped to frictionally interlock with the said dome when 70 they reach their slot-closing position.

4. In a lamp-burner of the character described, in combination with a slotted dome, the crown of which is curved on the arc of the circle, a pair of plates curved on an arc concentric with the dome-crown, means for pivotally mounting said plates on the dome whereby to freely swing to their down or normal position and out of contact and to frictionally engage the dome when swung in the 75 other direction to close over the dome-slot, each plate being eccentric to the curvature of the dome, means on the dome for loosely sustaining the plates at their open or normal position, the pivotal connection of the plates 80 being such that the plates are held from the crown when at their normal position, and whereby as either plate is swung over the crown-slot it will pass under the opposite plate and move into frictional engagement 85 with the crown as set forth.

5. In a burner of the character described, an extinguishing means comprising a pair of oppositely-disposed plates shaped to swing over the flame-slot in the burner-dome, means 90 for pivotally mounting said plates on the said dome whereby either of said plates will move over the slot in the dome and under the other plate when the lamp is turned, each plate having a portion to frictionally interlock with 95 the dome when swung over the slot therein, for the purposes specified.

6. The combination with the slotted dome portion of the burner, said portion being curved on the arc of a circle; of a pair of oppositely-disposed plates, each curved concentrically to the curve of the dome, each plate being pivotally mounted on the outside of the dome to swing over the slot in the dome when the lamp is tipped, the pivots being eccentrically arranged with respect to the curvature of the slotted dome, each of said plates when swung down to their normal or open position, being held out of contact with the slotted dome, means projected from the 100 dome for sustaining the plates at their normal position, the pivotal connection of the said plates to the dome being such that when either of the said plates is swung over the slot in the dome, it will frictionally engage with 105 the dome and be thereby held to its closed position.
